[57] CLAIM

The ornamental design for a novelty headgear, as shown and described.

DESCRIPTION

FIG. 1 is a perspective view of a novelty headgear showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an exploded front perspective view of a novelty headgear thereof;

FIG. 9 is a front elevational view thereof, the broken line showing of the human form is for illustrative purposes only and forms no part of the claimed design;

FIG. 10 is a top plan view of a second embodiment of novelty headgear showing my new design;

FIG. 11 is a bottom plan view thereof;

FIG. 12 is a front elevational view thereof;

FIG. 13 is a rear elevational view thereof;

FIG. 14 is a left side elevational view thereof; and

FIG. 15 is a right side elevational view thereof.
